HYDRAULIC PUMP OR MOTOR

Elek K. Benedek, Bucyrus, Ohio

Application November 20, 1935, Serial No. 50,671

4 Claims. (Cl. 103—161)

This invention relates to high pressure variable displacement, reversible, radial piston pumps and motors and particularly to efficient driving and load connections between the piston and cylinder assemblies and the reactance means.

One of the principal objects of the present invention is to provide a connection between the pistons and associated reactance in which the mass and inertia of the reciprocating parts of the connection is so reduced that mass and inertia forces resulting from high speed reciprocation are reduced to a minimum.

A correlative object is to accomplish this result without a sacrifice in strength of the reciprocating parts.

Another object is to reduce the number of parts necessary for the connection between the piston and reactance to a minimum.

Another and more general object is to provide for anti-friction driving transmission between the barrel and the reactance in a manner such that high efficiency can be provided at high commercial pressures and speed and accurate synchronization of the speeds of the rotors can be maintained under all conditions of operation.

Other objects and advantages will become apparent from the following specification wherein reference is made to the drawings in which

Fig. 1 is a longitudinal sectional view of a pump or motor embodying the principles of the present invention;

Fig. 2 is a cross sectional view taken on the plane indicated by the line 2—2 of Fig. 1;

Fig. 3 is a fragmentary sectional view of the piston head and associated reactance rings and is taken on a plane indicated by the line 3—3 in Fig. 2;

Fig. 4 is an elevation of a piston and crosspins illustrating the geometric relations thereof;

Fig. 5 is an elevation of a piston and crosspin illustrating a slight modification of the structure of Fig. 4;

Fig. 6 is a fragmentary elevation of a reactance ring used in connection with the piston structure of Fig. 5;

Figs. 7 and 8 are diagrammatic illustrations showing comparatively certain stress relations of the prior art and present piston head structure;

Fig. 9 is a fragmentary sectional view similar to Fig. 2 illustrating a modified piston head and reactance combination;

Fig. 10 is a cross sectional view taken on a plane indicated by the line 10—10 in Fig. 9;

Fig. 11 is a sectional view taken on the plane indicated by the line 11—11 in Fig. 10;

Fig. 12 is a fragmentary view of the reactance ring shown in Fig. 11 illustrating certain operating characteristics and relations of the ring and crosspins for load and torque transmission;

Fig. 13 is a longitudinal sectional view of a pump or motor illustrating a modified piston head and reactance combination and is taken on a plane indicated by the line 13—13 in Fig. 14;

Fig. 14 is a cross sectional view taken on the plane indicated by the line 14—14 in Fig. 13;

Figs. 15 and 16 are an elevation and plan view respectively of one of the pistons and crossheads of Fig. 14;

Fig. 17 is a longitudinal cross sectional view of part of a pump or motor structure and is taken on a plane indicated by the line 17—17 of Fig. 18;

Fig. 18 is a cross sectional view taken on a plane indicated by the line 18—18 of Fig. 17;

Fig. 19 is an elevation of one of the pistons and associated heads of Fig. 18;

Fig. 20 is a fragmentary plan view of a portion of the barrel and associated piston of Fig. 18 as viewed from the plane indicated by the line 20—20 of Fig. 18;

Fig. 21 is a cross sectional view taken on a plane indicated by the line 21—21 in Fig. 13 and illustrates the barrel mounting thereof and of Fig. 17;

Fig. 22 is an elevation of one of the crosspins utilized in the structure of Fig. 17; and

Figs. 23 and 24 are enlarged diagrammatic illustrations of the needle rollers mounting the crosspins of the present invention, and illustrate also operating characteristics of other needle bearings herein shown.

Referring first to Figs. 1 to 4 inclusive, the present invention is shown embodied in a pumping structure wherein a rotary reactance is employed, its use in connection with pumps and motors of the oscillating radial crosshead type, being apparent therefrom. The pump includes a rigid weight supporting casing 1, in which is mounted a valve pintle 2, having reversible valve ports 3 and 4 for valving cooperation with the cylinders, later to be described. The ports 3 and 4 are connected by suitable pairs of ducts 5 and 6 respectively with diametrically opposite main ports 7 and 8 respectively in the pintle, the main ports, in turn, being connected through suitable ducts, not shown, formed in the housing 1 with an external fluid circuit.

A cylinder barrel 10 having an axial bore 10a is rotatably mounted in the casing on heavy duty full complement tapered rollers 11, arranged one set at each end of the barrel and securing the

barrel in fixed axial and radial position within the housing. Positive but slight radial clearance between the barrel bore and pintle 2 is maintained by sets of elongated free rollers 12 and 13 respectively, arranged one set at each end of the pintle and operating on raceways formed directly on the pintle.

The barrel has a plurality of radial cylinders 14, each having a cylinder port 15 for cooperation successively with the ports 3 and 4 as the barrel rotates.

Mounted one in each cylinder are pistons 16, each having an enlarged head 17 elongated fore and aft from the axis of the associated piston, and of greater dimension radially of the pump or motor than transversely, that is, than parallel to the rotative axis. Each head 17 is preferably formed integral with the associated piston and has an elongated chordal operating way 17a by which it is associated with the rotary reactance through the medium of thrust pins 18 in rolling engagement with the way 17a. The operating way 17a is preferably in separate fore and aft portions, a reinforcing bridge 17b being left therebetween to provide additional rigidity.

The rotary reactance comprises a pair of axially spaced rings 19 disposed one at each of the lateral faces of the piston heads, the rings being secured together in coaxial relation with each other by means of suitable bolts 20 and accurate spacing of the rings being maintained by spacing sleeve 21, carried on the bolts 20. Thus the rings are drawn firmly into axially spaced relation to provide a circumferential recess accommodating the heads 17 with operating clearance only.

As better illustrated in Fig. 3, each of the crosspins 18 extends beyond the lateral limits of the associated head 17, the extending ends of each pin being rotatably mounted in aligned bores in the rings 19. For mounting the pins by their ends in the rings 19 for free rotation about their respective axes and for reducing the frictional resistance to rotation of the end portions of the pins to an amount less than the rolling frictional resistance of the mid portions in the ways 17a, the ends of the pins are mounted in capillary cageless needle rollers 22. The outer end portions of the pins 18 extend beyond the outer radial faces of the rings 19 and are circumferentially recessed adjacent the plane of the outer radial faces of the rings for receiving suitable retaining means such as snap washers 24 which constrain the pins in cooperative relation with the rings and piston heads while permitting free rotation thereof. In the form illustrated, the washers 24 may also act as retaining washers for the needle bearings 22 at their outer ends. The rings 19, in turn, are mounted in an adjustable stator 25, both on the same set of elongated rollers 26 so that they rotate therein freely and as a single unitary structure. Adjustment of the stator for varying the eccentricity of the rings with respect to the barrel is effected through the medium of a control rod 27.

In the structure described, the piston heads 17 and the slots therein must be made with extreme accuracy as also must the mounting of the pins in the rotary reactance rings 19 and all parts must be accurately assembled as the pins are fixedly secured in the rings and the pistons are fixed with respect to their associated crossheads, since no provision is made for adjustment of the working parts after the assembly and the original manufacture and assembly of the barrel, cylin-

ders, pistons, crossheads and pins must be maintained to the required accuracy for alignment.

Referring next to Figs. 7 and 8, one of the principal advantages of the present crossheads is diagrammatically illustrated. Heretofore the usual piston T-head, with which the present structure is most nearly comparable, when viewed in cross section as indicated at A in Fig. 7, has its minor axis disposed parallel to the piston axis and consequently in the direction of load application, indicated by the arrow L. Its dimension, therefore, in the direction of load is far less than normal to the load. Obviously, the load, in the direction of the arrow L, tends to warp the head and is not as effectively resisted as in the case of the present structure, illustrated in Fig. 8. In this structure the head in cross section B has its major axis parallel to the piston axis or direction of load, indicated by the arrow M.

The strength of a beam is proportional with its moment of inertia or section modulus, wherein b is the width and d is the depth in the direction of load application. It is apparent, therefore, that the present structure can withstand many times the load of the structure illustrated in Fig. 7 under similar stresses and with the same elastic or permanent deformation even though the cross section area A and B of the two heads are the same. Again, due to the greater section modulus for resisting the piston load, a much lighter construction may be used for the same load with heads made in accordance with the present invention. Again, due to the nature of section modulus, a head disposed such as in Fig. 8 is not appreciably weakened by the removal of material for forming the ways 17a as the ways are disposed close to and preferably symmetrical with respect to the neutral axis which is normal to the load, hereinafter referred to as the "normal neutral axis". Consequently, ample material remains for both compression and tension remote from the normal neutral axis. Thus not only may the ways be provided without an appreciable weakening of the structure, but also the head structure is made lighter in weight so that inertia forces due to high speed reciprocation are greatly reduced. As a result, the present head structure and its relation to the piston load makes possible the connections between the head and secondary rotor which were not practicable with the heads heretofore used and such as illustrated in Fig. 7.

The present design, however, requires precision and a disposition of the common plane X_1-X_1 of the axes of the crosshead pins normal to the axis X_2-X_2 of the piston, as illustrated in Fig. 4, the plane X_1-X_1 being the normal neutral axis of the crosshead.

In order to make an efficient pump or motor, and provide for free rotation of the rolling pins 18 with respect to the rings 19, and free rolling engagement thereof with the head 17, the rolling pins 18 must remain in the position wherein their axes are parallel and define a plane normal to the piston axis. Referring to Fig. 9, the requirement for this accurate relation is illustrated diagrammatically.

For providing this relation in manufacture, the ways 17a are formed accurately at right angles to the piston axis. The crosspins are to be positioned in the rotary reactance rings 19 with their axes in a circle f , as illustrated in Fig. 2, which is concentric with the rings 19, an operation which may readily be accomplished by the usual dividing head machine tool. All that is then necessary is to take precision dividers,

such as a compass, and measure to each side of the piston axis the same distance and the intersection of the arc or line thus drawn with the circle f described, locates accurately the axes of the crosspins in the rings 19. This layout can be applied in connection with the pistons and their crossheads by measurement to each side of the piston axis so that when the parts are finished, accurate coaction and proper relative positions between the radial axis of the cylinders and the crosspins, as well as the chordal plane defined by the axes of the associated crosspins, is provided. As a result, efficient operation will not be dependent upon self-aligning movement of any parts with respect to others but positive freedom is provided initially through the simple nature of the structure. This coaction is maintained as elastic and permanent deformations are very slight in the present heads. At the same time, the layout and manufacture is comparatively simple.

Referring next to Figs. 5 and 6, a somewhat similar cooperation is provided, the crosspins being rotatably mounted in the head of the piston with the operating ways in the reactance. For example, in Fig. 5 each piston 25 has a crosshead 26 disposed with the major axis of its cross section parallel to the piston axis. Rolling thrust pins 27 are mounted on capillary rollers 28 in the head 26, the axis of the rollers 28 lying in a plane normal to the piston axis. In the co-operating reactance rings 29, as illustrated in Fig. 6, are chordal ways 29a which likewise lie in the plane defined by the ends of the crosspins and accommodate the ends of the pins for rolling coaction therewith to compensate for tangential components of eccentricity of the cylinder rotor and reactance rotor.

Carrying the development a step further, there is illustrated in Figs. 9 to 12 inclusive, a cross-head of this general character having separate load transmitting and torque transmitting rolling pins. In this structure, a barrel 30 having radial cylinders 31 is provided, each cylinder 31 carrying a radial piston 32 having a head 33 corresponding in shape generally to the head 17 heretofore described. The head 33 is also tapered from the mid portion toward the ends so as to provide as near as may be a constant strength beam.

Rotatably mounted in the head 33 with its axis intersecting the piston axis is a load transmitting rolling pin 34 having reduced diameter end portions 34a. The pin is mounted in the head 33 on capillary cageless needle rollers 35. In advance of and to the rear of the pin 34 and equidistant from the axis thereof are torque transmitting rolling pins 36 each having reduced diameter end portions 36a. The pins 35 are also mounted on capillary cageless needle rollers 37 in the head 33. The rollers 36 are disposed with their axes in a plane through the axis of the roller 34 and normal to the piston axis. The rolling pins 34 act as rolling load transmitting means and since each pin carries the direct thrust of the associated piston substantially in the line of the piston axis, each pin 34 acts as means for reinforcing the associated piston head substantially in the zone of the piston axis.

Rotary reactance rings 38 are provided for coaction with the piston heads and pins and lie alongside the opposite faces of the heads, the rings being secured together by suitable bolts 39, the accurate axial spacing of the rings 38 being maintained by spacers 40. The rings, in turn,

are rotatably mounted in a stator 41 which operates in the usual manner. The rings 38 have axially aligned chordal ways, each way comprising a radially wide portion 38a for rolling and oscillating coaction with the ends 34a of the load pin 34, and symmetrical end portions 38b of less radial dimension, the end portions coacting with ends 36a of the torque transmitting rolling pins 36.

The specific operation of this structure is best illustrated in Fig. 12. Assuming the barrel to be driven in a clockwise direction, it is apparent that the hydraulic load will be taken by the pin 34 which, though oscillating along its slots 38a, applies the load within the projected area 15 of the piston. In effecting the torque transmission, there is a very slight rocking of the head which causes engagement of the leading roller 36 with the radially inward operating surfaces of the ways 38b, and the trailing rollers 20 36 with the outer operating surfaces of the associated ways 38b, thus providing positive torque transmission. Necessarily any such rocking is about the axis of the pin 34, as illustrated by the dot and dash lines in Fig. 12, but the relative 25 positions of the axes of the pins 36 and the axis of the pistons are necessarily fixed at right angles at all times.

In Fig. 12, the actual clearance between the ends 36a and cooperating surfaces of the ways 30 38b is greatly exaggerated for purposes of clearness in illustration. The actual clearance is such that if the radial clearance for the main thrust or load pin 34 is given, the clearance for the pins 36 would be very slightly more so as to assure 35 that the load will be primarily applied by the pin 34 and not by the pins 36.

Obviously, in such a structure, excessive wear would affect the operation and consequently all surfaces are made of non-wearing material such 40 as nitrallloy or the equivalent. Preferably nitrallloy pins having a surface hardness of 1000 Brinell and reactance rings having corresponding hardness are used, as the wear in such instance is not sufficient to appreciably affect the operation. 45

Referring next to Figs. 13 and 14, this structure utilizes a circular path of oscillation f_1 , corresponding to the circle f in Fig. 2, for the piston connections with the rings of the secondary rotor. In this structure, the cylinder barrel 45 having radial cylinders 46 is shown. Pistons 47 are carried in the cylinders 46 respectively and each has a head 48 of greater dimension in the direction of load application than transversely thereof, in the same manner as the heads heretofore described. The reactance comprises rings 49, which are mounted for independent axial and floating movement in a stator 50 on free cageless rollers operating in and guided at the ends by circumferential recesses in the stator. The rings 49 have aligned bores which receive rolling cross-pins 51. Each of the pins 51 has an enlarged central portion, and reduced end portions 51a. 60 The reduced end portions of each pin are mounted on capillary cageless rollers in aligned bores of the rings 49 and extend beyond the outer radial faces of the rings 49. The ends of the pins are recessed to receive snap washers 52 which 70 engage the outer radial faces of the rings and constrain them from axial operation. The larger central portions of the pins 51 provide radial shoulders for retaining the capillary rollers in the respective bores and for maintaining the rings 75

in proper axially spaced relation by rolling engagement therewith.

Each head 48 has an arcuate slot or operating way 48a which accommodates the enlarged central portion of the associated pin 51 and is in rolling engagement therewith, slight operating clearance being provided. The operating ways are segments of circles concentric with the rings 49. The axis of the pin 51 is parallel with the axis of rotation of the barrel and rings 49 and normal to the longitudinal axis of the head. The central portion of the pin 51 is of such diameter relative to the piston that the radial hydraulic piston load will be applied within the projected area of the piston in the arcuate way of the head so that there is a rigid, non-yielding load application between the piston and pin. The tangential rolling reciprocation of the pin in the way 48a will not be more than the diameter of the piston and as a result of this manner of applying the load, a very light crosshead structure can be utilized so that the inertia of the high speed rotation and reciprocation is reduced. For this same reason, the pistons may be made of duraluminum.

Another very important feature is the simplified movement and relation between the cylinder barrel and the reactance rotor rings. The pistons and heads are preferably made of a single piece of material forged to the proper shape. Due to the fact that the rolling pins 51 are mounted anti-frictionally in the rings 49, the resistance to rotation thereof in the rings is less than the rolling frictional engagement of the pins with the operating surfaces of the ways 48a as a result of which anti-friction rolling cooperation is provided and binding and sliding of the pins in the ways are eliminated. The barrel 45 is mounted on rollers 53 and coacts with a valve pintle 54, sets of full complement rollers 55 and 56 being interposed between the pintle and barrel. In the form illustrated, an impeller 57 is carried on the barrel.

Referring next to Figs. 17 to 22 inclusive, there is illustrated a barrel 60 having a radial flange 61 and radial cylinders 62 in the zone of the flange. The reactance comprises a stator 63 which rotatably supports axially spaced reactance rings 64. Mounted in each cylinder is a piston 65 having a crosshead 66 which is accommodated between the rings 64 with operating clearance only. The flange 61 has a plurality of radial guideways 67 aligned with the cylinders respectively, the guideways having cylindrical end walls snugly engaging complementary end walls of the heads 66 so as to prevent lateral rocking of the heads and for transmitting torque.

Each head 66 has an arcuate slot or way 66a corresponding to the way 48a of the structure of Fig. 14. Correspondingly crosspins 68 having relatively large central portions 68a and reduced end portions 68b are mounted in the reactance rings 64 by the reduced end portions. The central portion 68a of each pin is in rolling cooperation with the walls of the way 66a, the reduced end portions 68b being received in aligned bores in the rings 64 and mounted therein on capillary cageless needles 69. The outermost ends of the pins 68 are provided with recesses 68c in which are disposed suitable snap washers 70 for maintaining the pins in the rings 64 and constraining the rings against axial separation. Here again, due to the anti-friction mounting of the ends 68b of the pins 68 in the rings 64, rolling cooperation

only between the central portion 68a of the pins and the ways 66a is provided.

In this construction there is combined the load application to the piston along a circular path f_2 corresponding to the circle f of Fig. 2, and a piston crosshead which is fixed in relation to the piston, whereas heretofore piston structures in which the load is applied along an arcuate path employed the pistons which were separated from the heads so as to provide for self-adjustment. This structure is made possible by the cooperation of the head and guideways 67. When the piston and head are separated, as in prior structures, there is a rocking movement with respect to the crosspin and the piston so that the crosshead describes a semi-crank motion which imposes a substantial destructive tangential component of load on the piston through the crosspin, and upon the cylinder walls. In the present structure, however, since the head is well guided and supported by the guideways 67, and unnecessary heavy reciprocating ports are eliminated by mounting the pins in the reactance rings instead of directly in the head, this rocking action is reduced or eliminated and is prevented from reaching the pistons in a degree sufficient to cause wear and binding. The ways 66a necessarily lighten the reciprocating head so that high speed and high pressures as great as may be necessary may be provided. In all the forms of the invention hereinbefore illustrated, the axes of the rolling pins and the operating ways are disposed at the normal axis of the associated heads.

Referring to Figs. 23 and 24, an unusual operating phenomenon resulting from the use of capillary rollers is shown as mounted between two members X and Y which are relatively rotatable, one such member being a reactance ring or piston head, and the other being a thrust pin. The capillary cageless rollers are disposed between the members X and Y with a total circumferential clearance equal from slightly less than 1 to about 2 needles. For example, the needles may be packed between the members X and Y and then one or two needles of the full complement removed. The needles operate in an oil bath, which, in the present pump, is provided by slip fluid. Assuming the load to be applied to the member X, in the direction of the arrows Z_1 and Z_2 in Figs. 23 and 24 respectively, an unexpected reaction occurs. It is found that the needles crowd to the loaded zone instead of being driven away or squeezed out from under the load. The needles opposite the loaded zone correspondingly separate circumferentially as indicated by the arrows s . Upon the separating of the needles, as indicated by the arrows s , the resultant clearance space between the unloaded needles sucks in oil. Obviously in a reciprocating member wherein the load is first applied in one direction as indicated in Fig. 23, and then in the opposite direction as indicated in Fig. 24, full complement bearing for load is provided with a separation of the needles at the unloaded side for receiving oil. Upon reversal of the operation, as upon the suction stroke, the opposite side becomes loaded and the needles rush to the said opposite side, again assuming the load and separating the first, and now unloaded side, again replenishing the oil. Thus each needle of the set may rotate freely about its own axis unconstrained by adjacent needles and remain in rolling engagement with both races due to capillary oil films, and full rolling bearing surface at the instantaneous loaded side is provided.

Having thus described my invention,
I claim:

1. In a hydraulic machine of the class described including a plurality of rotatable radially disposed piston and cylinder assemblies, the pistons being reciprocable relatively to the cylinders and having rigid piston heads thereon, a rotary support having radial wall portions lying alongside the piston heads, each piston head being elongated fore and aft from the axis of the associated piston and relatively wide in the plane of the pistons, operating ways in the heads extending entirely therethrough transversely of the heads both fore and aft of the piston axis, transverse rollers for each head mounted at their ends in said radial walls and in rolling cooperation with said ways, said rollers being positioned in advance and in rear of the piston axis of the associated head, and reinforcing bridges in the heads at the longitudinal mid portions of the operating ways.

2. In a hydraulic machine of the class described including a plurality of rotatable, radially disposed piston and cylinder assemblies, each comprising a relatively reciprocable element and a relatively non-reciprocable element, the relatively reciprocable elements having rigid heads thereon respectively, a rotary support having radial wall portions lying alongside the heads, each head being elongated fore and aft from the axis of the associated piston and cylinder assembly and relatively wide in the plane of the reciprocable elements, operating ways in the heads extending entirely therethrough transversely of the heads both fore and aft of the associated piston and cylinder axis, transverse rollers for each head mounted at their ends in said radial walls and in rolling cooperation with said ways, said rollers being positioned in advance and in rear of the piston and cylinder axis of the associated head, and reinforcing bridges in the heads at the longitudinal mid portions of the operating ways.

3. In a hydraulic machine of the class de-

scribed including a plurality of rotatable, radially disposed piston and cylinder assemblies, each comprising a relatively reciprocable element and a relatively non-reciprocable element, the relatively reciprocable elements having rigid heads thereon respectively, a rotary support having radial wall portions lying alongside the heads, each head being elongated fore and aft from the axis of the associated piston and cylinder assembly, operating ways in the heads extending entirely therethrough transversely of the heads both fore and aft of the associated piston and cylinder axis, transverse rollers for each head mounted at their ends in said radial walls and in rolling cooperation with said ways, said rollers being positioned in advance and in rear of the piston and cylinder axis of the associated head, and reinforcing bridges in the heads at the longitudinal mid portions of the operating ways.

4. In a hydraulic machine of the class described including a plurality of rotatable, radially disposed piston and cylinder assemblies, each comprising a relatively reciprocable element and a relatively non-reciprocable element, the relatively reciprocable elements having rigid head members thereon respectively, a rotary support member having radial flange portions lying alongside the head members, each head member being elongated fore and aft from the axis of the associated piston and cylinder assembly, and there being associated with each piston and cylinder assembly an elongated operating way in one of the said members both fore and aft of the associated piston and cylinder axis and two transverse rollers spaced fore and aft of said associated piston and cylinder axis and each having rolling engagement with the way in one member and being journaled in said other member, and reinforcing means for said heads substantially in the line of the respectively associated piston and cylinder axes.

ELEK K. BENEDEK.
